UNITED STATES PATENT OFFICE.

THEODORE J. LOWERY, OF WASHINGTON, DISTRICT OF COLUMBIA.

DESIGN FOR A BAR-PIN OR SIMILAR ARTICLE.

45,998.

Specification for Design.

Patented June 23, 1914.

Application filed February 26, 1914. Serial No. 821,313. Term of patent 3½ years.

To all whom it may concern:

Be it known that I, THEODORE J. LOWERY, a citizen of the United States, residing at No. 1421 F street northwest, Washington, District of Columbia, have invented a new, original, and ornamental Design for a Bar-Pin or Similar Article, of which the following is a specification, reference being had to the accompanying drawing, forming part thereof.

The figure is a plan view of a bar-pin; showing my new design.

I claim:

The ornamental design for a bar-pin or similar article as shown.

THEODORE J. LOWERY.

Witnesses:

W.M. S. MINNIX,
CHARLES E. ROWE.
